UNITED STATES PATENT OFFICE.

STEVE ZUNAC, OF COALDALE, PENNSYLVANIA.

PERMUTATION-LOCK.

Specification of Letters Patent. Patented Aug. 28, 1917.

1,238,617.

Application filed November 17, 1916. Serial No. 131,876.

To all whom it may concern:

Be it known that I, STEVE ZUNAC, a citizen of the United States, residing at Coal-
dale, in the county of Schuylkill and State
of Pennsylvania, have invented certain new
and useful Improvements in Permutation-
Locks, of which the following is a specifica-
tion.

The present invention relates to certain
new and useful improvements in push pin
permutation locks, and has for its object to
provide a device of this character which em-
bodies novel features of construction whereby
the locking member, such as a sliding
bolt, is withdrawn from operative position
as the push pins are manipulated, no opera-
tion such as the turning of a knob subse-
quent to the manipulation of the push pins
being necessary.

Further objects of the invention are to
provide a device of this character which
may be used with equal effectiveness upon
large doors, such as found upon vaults, or
smaller doors, such as are found upon small
containers in the nature of safe deposit
boxes.

Another object of the invention is to pro-
vide a permutation lock which is simple and
inexpensive in its construction, and which
can be easily and quickly operated.

With these and other objects in view, the
invention consists in certain novel combina-
tions and arrangements of the parts as will
more fully appear as the description pro-
ceeds, the novel features thereof being
pointed out in the appended claims.

For a full understanding of the in-
vention, reference is to be had to the following
description and accompanying drawings, in
which:

Figure 1 is a front elevation of one of a
pair of members adapted to be locked to-
gether, showing the manner of applying a
lock constructed in accordance with the in-
vention thereto, portions being broken away.

Fig. 2 is a rear elevation of the same,
showing the lock in an operative position.

Fig. 3 is an edge view thereof.

Fig. 4 is a transverse vertical sectional
view taken on the line 4-4 of Fig. 2, and
looking in the direction of the arrows, the
tumbler being shown in a partially raised
position.

Fig. 5 is a detail perspective view of the
tumbler and the trip plate carried thereby
removed from the lock.

Fig. 6 is a view similar to Fig. 4, showing
a modification in the mounting of the push
pins, the tumbler being removed.

Fig. 7 is a rear elevation of the arrange-
ment shown by Fig. 6, the cover plate and
springs being removed.

Corresponding and like parts are referred
to in the following description and indi-
cated in all the views of the drawings by
the same reference characters.

It will be understood that this invention
may be applied to either the movable or the
stationary one of the two members to be
locked together, and the operation of the
lock is exactly the same whether used upon
the stationary or the movable member. Re-
ferring to the drawings, the numeral 1 des-
ignates one of a pair of members to be locked
together, and the numerals 2 a plurality of
push pins which are slidably mounted in
the member 1. It will be obvious that the
push pins 2 may be constructed in any de-
sired configuration, although in the present
instance they are shown as substantially dia-
mond shaped. The pins 2 are loosely
mounted within correspondingly shaped
openings 3 in the member 1, the said open-
ings being so arranged as to form the out-
line of a diamond. One object of this ar-
rangement is to economize in the space con-
sumed by the pins, although it also adds to
the attractiveness of the lock. The exposed
ends of the pins are designed to carry some
suitable and varied inscriptions or charac-
ters, and in the present instance each pin
bears a different number, although it will be
obvious that letters or other characters may
be substituted for the numbers. While not
necessary, it is desirable to provide the pins
with interchangeable heads or faces, so as to
provide means for readily changing the
combination of the lock. One possible con-
struction is shown in detail by Fig. 4,
wherein the numeral 4 designates a shell 100
similar to the shell of the ordinary type-
writer key, the said shell having arranged
therein an inscription carrying disk 5 and a
glass or mica plate 6 arranged thereover so
as to protect the same from defacement. 105
The inner end of the shell 4 is provided
with a threaded stud 7 adapted to fit within
a correspondingly threaded opening 8 in
each of the push pins 2. With this con-
struction it will be seen that the combina-
tion of the lock may be easily and quickly
changed by simply interchanging the re-

movable heads or faces on the push pins. The member 1 is provided on its inner side with a recess 9 with which the openings 3 in which the push pins are mounted communicate. Each of the push pins is provided at an intermediate point in its length with a flange 10, which is adapted to abut against the base of the recess 9 to prevent the pins 2 from being forced outwardly 5 through the member 1 from the inside thereof. A cover plate 11 normally closes the recess 9 in the member 1, the said cover plate being provided with openings 12 adapted to receive the cylindrical reduced portions 13 10 upon the inner ends of the push pins 2. Coil springs 14 surround the said cylindrical reduced portions of the pins and are interposed between the inner side of the cover plate 11 and the flanges 10, so as to normally force the pins outwardly. The extreme inner ends of the reduced cylindrical portions 13 of the push pins which project through the cover plate 11 are rounded or beveled, as indicated at 15, so as to coöperate 15 with the beveled face 16 of a tumbler 17 which is pivoted upon the cover plate 11, by means of a pivot bolt 18. The tumbler 17 is clearly indicated by Fig. 5, and is adapted to swing across the inner ends of the push pins 2 about its pivot bolt 18. This tumbler 17 comprises a bar of any desirable material, preferably steel, and is provided for a portion of its length on the side thereof adjacent the push pins 2 with 20 the beveled or inclined surface 16 above mentioned. When one of the push pins 2 is forced inwardly against the action of the spring 14 and its rounded end 15 engages the beveled or inclined surface 16 on the tumbler 25 17 at the proper point, it will be obvious that the tumbler will be swung upwardly a certain distance about its pivot bolt 18, and that when another pin at a higher elevation is forced inwardly and engages the inclined 30 surface 16, the tumbler will be swung still higher about its pivot bolt 18. However, only certain pins will engage the inclined surface at the proper point to raise the tumbler in the required manner, and these pins 35 must be operated in the proper succession. It will be clear therefore from the above explanation that these certain pins form the combination of the lock, and that this combination must be known before the lock can 40 be successfully operated. A guide bolt 19 is arranged on the outside of the swinging end of the tumbler 17 and is supported by eye brackets 20 secured to the cover plate 11. The object of this guide bolt is to prevent 45 the tumbler from being sprung outwardly should a wrong pin be operated and strike the tumbler at a wrong point on the inclined surface 16.

It is necessary that the tumbler 17 be temporarily locked in each successive position to

which it is raised by the operation of the successive pins, and for this purpose the swinging end of the tumbler is provided with a longitudinally projecting pin 21 which is adapted to engage the teeth 22 on a ratchet bar 23 arranged adjacent the swinging end of the tumbler. This ratchet bar 23 is pivotally mounted at its upper end, as indicated at 24, to an outwardly projecting bracket 25 rigidly secured to the cover plate 11. A spring wire or strip 26 has one end thereof rigidly secured to the cover plate 11, while the other end is pivotally connected at 27 to the ratchet bar 23, the object of said spring 26 being to normally hold the ratchet bar in engagement with the pin 21 on the tumbler 17. The lower end of the ratchet bar 23 is loosely mounted within a guide loop 28 which projects outwardly from the cover plate 11, the object of said guide loop being to limit the swinging movement of the ratchet bar about its pivot and to prevent displacement thereof beyond the end of the pin 21. As the tumbler is raised by the action of one of the pins on the inclined surface 16 thereof, the pin 21 forces the ratchet bar 23 outwardly about its pivot and against the action of the spring 26, until the tumbler has been raised to the limit possible by that particular pin, when the pin 21 engages the nearest tooth 22 on the ratchet bar, the spring 26 holding the ratchet bar in close engagement with the pin 21. The tumbler 17 is thus temporarily supported in this position until the operation of the next proper pin, when the pin 21 will slip upwardly by the teeth 22 of the ratchet bar until the tumbler is raised to the limit of this pin, when it will again engage one of the teeth on the ratchet bar 23. Thus the tumbler 17 is temporarily locked in its successive positions until it is raised to the point required to operate the locking member.

While the tumbler can be successfully operated only by manipulation of the proper push pins 2 in the required succession, means have been provided to further increase the effectiveness of the lock, namely, to force the tumbler into its original position should one or two of the proper pins be operated in the required succession and then a wrong pin manipulated. A trip plate 29 is pivotally mounted upon the outside of the tumbler 17, the said plate being arranged in a substantially vertical plane and extending the full length of the inclined surface 16. This plate 29 extends vertically downward at 29^a to a distance below the lower edge of the inclined surface 16 slightly greater than the diameter of the reduced cylindrical portions 13 of the push pins 2, and is then offset laterally and inwardly at 29^b to a short distance from the rounded ends of the push pins, and then vertically downwardly at 29^c. The vertical portion 29^c is adapted to swing across the

inner ends of the push pins as the tumbler is raised thereby, and should a pin lower than the proper pin be manipulated, it will be forced inwardly against the vertical portion 29^c of the trip plate 29, and the trip plate will be swung outwardly about its pivot. The outer end of the trip plate is provided with a laterally and longitudinally projecting arm 30, which is adapted to slide 10 within a slot 31 in the ratchet bar 23. It will be obvious from this construction that when the trip plate 29 is forced outwardly by the operation of a wrong pin, the ratchet bar 23 will be forced outwardly from engagement with the pin 21 on the tumbler 17 by the arm 30, thereby allowing the tumbler to fall back into its original position.

In order to operate the locking member to withdraw it from operative position as 20 the push pins are manipulated, the tumbler 17 is provided at a point between its pivot and its free end with a downwardly projecting arm 32. The outer end of this arm 32 is pivotally connected at 32^a to one end 25 of a link 33, the opposite end of the said link 33 being pivotally connected at 34 to one end of a lever 35 which is pivotally connected at an intermediate point in its length by a pivot bolt 36 to the cover plate 30 11. The opposite end of the said lever 35 is pivotally connected at 37 to a link 38 which is also pivotally connected at 39 to the base of a U-shaped sliding locking bolt 40, the arms 41 of which project outwardly 35 from the edge of the door to form in effect two locking bolts. The said locking bolt 40 is slidably mounted within a recess 42 formed on the inner face of the member 1, and the cover plate 11 serves to hold the 40 locking bolt 40 within the recess 42. The tumbler 17, link 33 and lever 35 are all arranged on the outside of the cover plate 11, and a slot 43 is formed in the cover plate to accommodate the pivot 39 connecting 45 the link 38 to the locking bolt 40. Springs 44 have one end thereof connected to the locking bolt 40 and the other end thereof to the member 1, the said springs serving to normally force the locking bolt 50 40 into locking position and in turn normally forcing the tumbler 17 into its lowest position through the medium of the link 38, lever 35, link 33, and the arm 32 rigidly connected to the tumbler.

55 When the lock is used on large doors, it will be seen that the lock may be operated from either side of the door, and in order to facilitate the unlocking of the door from the inside thereof, a knob 45 is applied to 60 the free end of the tumbler 17. When the tumbler is raised the locking bolt is simultaneously withdrawn through the action of the leverage above described.

In Figs. 6 and 7 of the drawing, a modified construction of mounting for the push

pins is illustrated. The pins are formed exactly as previously described, with the exception that the flanges 10 are omitted, and each of the pins is provided with an elongated slot 46 adapted to receive a wire 70 or rod 47. With reference to Fig. 7, it will be seen that the wires or rods 47 project diagonally through the various rows of pins 2, one wire being provided for each row, and the opposite ends of the wires being secured to the base of the recess 9 in the member 1, by means of screws 48. This construction is merely a substitution for the flanges 10 to hold the pins 2 in position within the openings 3 in the member 1. 80 The springs 14 act in exactly the same manner as previously described and the cylindrical reduced portions 13 project through the openings 12 in the cover plate 11 as previously explained.

85 As has been previously described, one means for changing the combination of the lock is to interchange the removable heads or faces on the push pins 2, and another means is to change the pivot point of the 90 tumbler 17. For this purpose the cover plate 11 may be provided with a plurality of extra threaded openings 49 in which the pivot bolt 18 may be inserted in order to change the pivot bolt of the tumbler 17. 95 To accommodate the changes of the pivot point of the tumbler, the link 33 and lever 35 are provided with a plurality of extra openings 50 to accommodate the pivot bolts 34 and 36.

100 Having thus described the invention, what I claim as new and desire to secure by Letters Patent, is:—

1. A permutation lock including a plurality of push pins mounted within one of 105 a pair of members to be locked together, the said push pins being provided with beveled inner ends, a tumbler having one end thereof pivotally connected to the said one of a pair of members to be locked together, 110 and having an inclined surface adapted to coöperate with the beveled ends of the push pins to swing the tumbler about its pivot, a rack bar adapted to engage the tumbler to temporarily lock the same in the positions to which it is moved by the push pins, a locking member, and an operative connection between the locking member and the tumbler.

2. A permutation lock including a plural- 120 ity of push pins mounted within one of a pair of members to be locked together, the said push pins being provided with beveled inner ends, a tumbler having one end thereof pivotally connected to the said one of a 125 pair of members to be locked together and having an inclined surface adapted to coöperate with the beveled ends of certain of the push pins to swing the tumbler about its pivot, a rack bar adapted to engage the tum- 130

- bler to temporarily lock the same in the positions to which it is moved by the push pins, means actuated by certain of the other push pins for forcing the rack bar from engagement with the tumbler thus allowing the same to assume its original position, a locking member, and an operative connection between the locking member and the tumbler.
3. A permutation lock including a plurality of push pins mounted within one of a pair of members to be locked together, the said push pins being provided with beveled inner ends, a tumbler having one end thereof pivotally connected to the said one of a pair of members to be locked together and having an inclined surface adapted to cooperate with the beveled ends of certain of the push pins to swing the tumbler about its pivot, a rack bar adapted to engage the tumbler to temporarily lock the same in the positions to which it is moved by the push pins, a trip plate mounted upon the tumbler and engaging the rack bar, the said trip plate being adapted to force the rack bar from engagement with the tumbler when certain of the other push pins are manipulated, a locking member, and an operative connection between the locking member and the tumbler.
4. A permutation lock including a plurality of push pins mounted within one of a pair of members to be locked together, a tumbler adapted to be actuated by certain of the push pins into various successive positions, means for temporarily holding the said tumbler in each of the said successive positions to which it is moved by certain of the push pins, a trip plate pivotally mounted upon the tumbler and engaging the said means for holding the tumbler in the successive positions to which it is moved by the push pins, the said trip member being adapted to be engaged by certain of the other push pins to force the said holding means for the tumbler from engagement therewith, a locking member, and an operative connection between the locking member and the tumbler.
5. A permutation lock including a plurality of push pins mounted within one of a pair of members to be locked together, a tumbler adapted to be actuated by certain of the push pins into various successive positions, a pin projecting from the tumbler and rigid therewith, a ratchet bar pivotally mounted at one of its ends to the said one of a pair of members to be locked together and normally engaging the said pin on the tumbler to support the tumbler in its successive positions, a trip plate pivotally mounted upon the tumbler, an arm project-

ing from said trip plate and having a slideable engagement with the said ratchet bar, the said trip plate being adapted to be actuated by certain of the other push pins to force the ratchet bar from engagement with the pin on the tumbler, a locking member, and an operative connection between the tumbler and the locking member.

6. A permutation lock including a plurality of push pins mounted within one of a pair of members to be locked together, a tumbler pivoted at one of its ends to the said one of a pair of members to be locked together and adapted to be swung about its pivot by the said push pin, an arm rigidly connected to the said tumbler and projecting laterally therefrom, a lever pivotally mounted between its ends to the said one of a pair of members to be locked together, a link connecting the said laterally projecting arm on the tumbler to one end of the said lever, a sliding locking bolt, and a link member connecting the said locking bolt to the opposite end of the said lever.

7. A permutation lock, including a plurality of push pins mounted within one of a pair of members to be locked together, said push pins having beveled inner ends, a tumbler comprising an elongated bar pivotally secured at one end thereof to the said one of a pair of members to be locked together, said tumbler being provided with a continuous and longitudinally extending inclined surface adapted to be engaged by the beveled ends of the said push pins to actuate the tumbler about its pivot, and locking means co-operating with the said tumbler.

8. A permutation lock, including a plurality of push pins mounted within one of a pair of members to be locked together, said push pins having beveled inner ends, a tumbler comprising an elongated bar pivotally mounted at one end thereof to the said one of a pair of members to be locked together, said tumbler being provided with a continuous and longitudinally extending inclined surface adapted to be engaged by certain of the push pins to actuate the tumbler about its pivot in one direction, means actuated by certain of the other push pins for forcing the tumbler about its pivot in the opposite direction, and locking means co-operating with the tumbler.

In testimony whereof I affix my signature in the presence of two witnesses.

STEVE ZUNAC.
